UNITED STATES PATENT OFFICE

JAMES E. ECKERSLEY, OF ABERDEEN, WASHINGTON, ASSIGNOR OF ONE-HALF TO
ALEXANDER POLSON, OF HOQUIAM, WASHINGTON

CIRCULAR KNIFE FOR WOODCUTTING MACHINES

Application filed October 30, 1929. Serial No. 403,576.

Knives used in shingle and veneer machines are subjected to tremendous strains, stresses and tension, due to heat resulting from friction in the material operated upon during the course of the cutting operation. In such knives built up in solid form, the rim or cutting edge has a tendency to wobble, or "snake", thereby causing the cutting of the stock in uneven thickness, which results in a loss to the manufacturer, because such uneven shingles or veneer must be classed as "seconds".

The primary object of my invention is to provide a sectional circular knife; that is, to say, a circular knife built up of independently removable sections, or segments, and to provide means to cool the cutting edge portion of each segment during its cutting action.

20 A further object of my invention is to provide means to interlock the abutting side edges of adjacent segments flush; and with these and other objects in view my invention consists of the parts and combination of 25 parts hereinafter pointed out.

In the drawings:

Figure 1 is a top plan view of a circular knife embodying my invention.

Figure 2 is an enlarged detail view of assembled segments of the knife.

Figure 3 is a front edge elevation of one of the segment knives.

Figure 4 is a detail top plan view of assembled segments.

35 Figures 5 to 11 are detail views of different means which may be used in assembling the segments to form the circular knife.

Figure 12 is a detail sectional view.

The reference numeral 14 designates the 40 base ring or plate of the knife which may be of any approved construction and desired size.

The segments 15 may be of any desired 45 size and number to fit the base ring 14 selected. These segments or knives are made in the shape of a segment and are provided with cutting edges 16 from which edge the knives are bevelled on their underside back to the point 17 (shown in dotted lines in Figures 1 and 2). At the outer corners the segments

are bevel-ground to the edge, the inner margin of the bevel being designated by the numeral 18, and these corners are bevelled or cut away as at 19. The object of these cut away or rounded corners 19 is to prevent 55 slivers from accumulating between the abutting edges of adjacent knife segments.

On the top side of each segment 15 I form 60 grooves 20 which extend substantially from the dotted line 17 towards the cutting edge 16, but stopping short of such edge. In the cutting action the cutting edge zone of a knife becomes heated; I eliminate this heating by placing water, or other cooling medium on the segments and by centrifugal action the 65 water is thrown outward until it enters the grooves 20 through which the cooling medium is distributed on the segment near its cutting edge and prevents undue heating of such edge.

The segments are secured to the plate 14 by means of screws 21, or other suitable means, the heads of which are countersunk in the segments.

In order to keep the abutting edges of adjacent segments flush and in the same plane I have adapted a number of expedients, some of which are shown in Figures 5 to 11.

In Figure 5 the edge of one of the segments is concaved as at 22 which the abutting edge of 80 the adjacent segment is concaved as at 23, forming in effect a tongue and groove joint. In Figures 6 and 8 the construction is a tongue and groove joint of different configuration.

In Figure 7 the abutting edges of adjacent segments are concaved as at 24 and a round key 25 is seated in said concaves 24.

Figure 9 shows in effect the same construction as is shown in Figure 7 except that the 90 joint is angular.

In Figure 10 the abutting edges of adjacent sections are each provided with a groove 26 into which a key 27 fits.

In Figure 2 I show a dumb bell key 28, and 95 a countersunk rivet 29.

As stated I do not limit myself to the key forms shown in Figures 5 to 11 as my invention in this particular contemplates means to firmly hold the abutting edges of adjacent 100

knife segments flush and in the same plane, and in the plane of the body of the segment.

I am aware that changes may be made in my improved circular knife without departing from the scope of the appended claims.

5 What I claim is:

1. In a circular knife, a circular knife bar, a plurality of knife segments secured to said bar side by side, the outer corners of said 10 knife segments converging toward a central radial line.
2. In a knife, a knife blade having grooves in its upper face designed to conduct a cooling medium toward the cutting edge portion.
- 15 3. In a knife, a knife blade having grooves in its upper face terminating at their outer ends short of the cutting edge of the blade.
4. In a circular knife, a circular knife bar, a plurality of knife segments secured to said 20 bar side by side, grooves in the upper faces of said segments terminating short of the cutting edge zone thereof and designed to supply a cooling medium to said zone.

In testimony whereof I affix my signature.

25 JAMES E. ECKERSLEY.
